UNITED STATES PATENT OFFICE.

OSTEEN J. PLAYER, OF ROCKINGHAM, NORTH CAROLINA, ASSIGNOR OF TWENTY-TWO AND ONE-HALF PER CENT TO H. L. LAWS, TWENTY-TWO AND ONE-HALF PER CENT TO E. H. BOWLING, TEN PER CENT TO G. T. McARTHUR, AND TEN PER CENT TO J. C. CLARKE, ALL OF DURHAM, NORTH CAROLINA.

SURE-FIND DROP WIRE.

Application filed January 8, 1925. Serial No. 1,300.

To all whom it may concern:

Be it known that I, OSTEEN J. PLAYER, a citizen of the United States, residing at Rockingham, in the county of Richmond and State of North Carolina, have invented certain new and useful Improvements in a Sure-Find Drop Wire, of which the following is a specification.

This invention relates to improvements in drop wires, steel heddles or detectors which are used in conjunction with the warp stop motion of looms, warpers and other like devices.

One of the important objects of the present invention is to provide means whereby the movement of a drop wire or detector to an operative position when the warp thread associated therewith has become broken or undue slackness in the thread has occurred may be readily and easily ascertained.

A further object is to provide a drop wire, steel heddle or warper for the warp stop motion of looms which includes a means for visually detecting the movement of the drop wire to an operative position when the warp thread has become broken, or slackness occurred therein.

Where a series of longitudinally movable drop wires or detectors are maintained in alignment in an inoperative position by the normal warp threads associated with the respective drop wires, or heddles, considerable difficulty is experienced in locating the drop wire or detector which has moved downwardly into an operative or indicating position by reason of the warp thread breaking or slack occurring therein, due to the fact that the drop wires are closely associated with each other and considerable time and labor is spent in locating the drop wire which has been lowered.

The present invention has for its principal object to provide a drop wire, or heddles wherein means is associated therewith for enabling a person to visibly detect one of a series of drop wires which has been lowered, thereby saving considerable time and labor.

A further object is to provide a drop wire wherein means is associated therewith for facilitating the raising or lifting of the same after the same has been lowered.

A further object is to provide a drop wire of the above mentioned character, which is simple in construction, inexpensive, strong and durable and further well adapted for the purposes for which it is designated.

Other objects and advantages will become apparent during the course of the following description.

In the accompanying drawing, forming a part of this specification, and in which like numerals designate like parts throughout the same:

Figure 1 is a perspective view of a series of drop wires or heddles or detectors showing the same mounted on a supporting or guide bar, and illustrating one of the drop wires or heddles disposed in an operative or indicating position.

Figure 2 is a side elevation of one of the drop wires or heddles embodying my invention.

Figure 3 is a side elevation of another form of a drop wire or heddle embodying my invention, and

Figure 4 is a side elevation of a still further form.

In the drawing wherein for the purpose of illustration is shown the preferred embodiment of my invention, with reference more particularly to Figures 1 and 2, the drop wire 1 is formed of a flat strip of metal, the same being of the requisite length and width. The drop wire 1 is provided with a circular opening 2 in the intermediate portion thereof which provides the usual warp eye for receiving the usual warp thread 3 in the manner well known in the art.

The upper portion of the drop wire or detector 1 is provided with a longitudinally extending slot 4 which provides a guide for the drop wire. The usual supporting or guide bar 5 extends transversely through the longitudinal slot 4 of each drop wire and normally the bar 5 is disposed in the lowermost portion of the slots in the series of aligned drop wires as clearly illustrated in Figure 1.

A projection 6 extends laterally from the upper end of the drop wire or heddle 1. The lateral projection 6 is disposed substantially adjacent the upper end of the longitudinal slot 4; by substantially adjacent I mean that

the projection is contiguous of or adjoins the upper end of the slot, and the purpose thereof will be presently apparent. To render the drop wire 1 light in weight, the upper 5 end thereof is provided with the cut out portion or opening 7 as more clearly illustrated in Figure 2.

When the series of drop wires or heddles are in their normal inoperative positions, 10 the projections 6 formed on the upper ends of the drop wires or heddles are in alignment with each other. As soon as one of the warp threads break or an undue slackness occurs, the drop wire associated with 15 such warp thread will move downwardly, the guide slot 4 permitting the vertical movement of the drop wire or heddle so that the upper portion of the slot will rest on the upper edge of the supporting bar 20 5. The drop wire which has been affected due to the breaking of the warp thread will have its projection 6 disposed out of alignment with the projections of the remaining series of drop wires or heddles in 25 a manner clearly illustrated in Figure 1 whereby the operator of the loom or warper may readily locate the drop wire, heddle, or detector which has moved to an operative position at a glance, thus obviating 30 the necessity of having to employ a drop wire or detector finder and which necessitates the loss of considerable time and labor.

The drop wire or heddle, which has been lowered, may be raised by engaging the 35 bottom edge of the lateral projection with a suitable hook or by placing the hook in engagement with the opening 7 independently of the slot 4 so that the drop wire may be readily and easily raised to its 40 level position in alignment with the remaining series of drop wires or heddles.

The provision of the lateral projection 45 6 affords a means for visually detecting or ascertaining at a glance the position of the drop wires or heddles. Ordinarily with the drop wires or heddles now in use, it is impossible to detect a drop wire or heddle which has been moved to an operative position through any visual means due to 50 the fact that the drop wires or heddles are closely associated with each other on the supporting bar or bars and are all arranged in vertical alignment. Furthermore, the drop wires, heddles, or detectors 55 now universally used are not provided with any projections or the like for the purposes above set forth.

In Figure 3 of the drawing, the upper 60 end of the drop wire or heddle is provided with an enlarged circular head 8 which provides a means for visually ascertaining the position of the drop wire or heddle when the latter is used in connection with single warp threads. In Figure 4 of the drawing, the visual detecting means provided 65

on the upper end of the drop wire or heddle is in the form of an offset substantially circular head as illustrated at 9.

The circular heads formed on the upper ends of the drop wires shown in the modification are each provided with an enlarged opening, the same being disposed above the upper ends of each of the longitudinal guide slots and these openings provide a means for receiving a hook to facilitate the 71 raising of the drop wire after the same has been lowered. The provision of the opening at a point above the upper end of the longitudinal slot in each of the drop wires will enable the drop wires to be readily 76 lifted or raised without necessitating the placing of the hooks which are employed for raising the drop wires in the longitudinal guide slots. When one of the warp threads is broken, the drop wire associated therewith will move downwardly so that the upper end of the longitudinal slot will rest on the upper edge of the supporting or guide bar thus rendering it impossible to raise the drop wire by inserting a 81 hook or other similar implement in the longitudinal slot.

It will thus be seen from the foregoing description, that a drop wire, heddle, or detector for warp stop motions of looms 95 has been provided which will at all times be positive and efficient in carrying out the purposes for which the same is designated, the simplicity in which the device is constructed furthermore enabling the same to 100 be manufactured at a very low cost.

While I have shown the preferred embodiment of my invention, it is to be understood that various changes in the size, shape, and arrangement of parts may be 105 resorted to, without departing from the spirit of the invention and the scope of the appended claims.

Having thus described the invention, what I claim is:—

1. In a drop wire for looms wherein the same is provided with the usual longitudinal guide slot in the upper portion thereof to receive the usual guide bar, and a warp thread receiving opening below said 115 slot, of means extending beyond the side edge of the upper portion of the drop wire at a point adjoining the upper end of the slot whereby the drop wire may be readily visible when the same becomes lowered, said 120 means being provided with a hook receiving opening to facilitate the raising of the drop wire, the opening being formed at a point above the upper end of the longitudinal guide slot.

2. In a drop wire for looms wherein the same is provided with the usual longitudinal guide slot in the upper portion thereof to receive the usual guide bar, of means 125 extending beyond the side edge of the up-

per portion of the drop wire at a point above the upper end of the longitudinal adjoining the upper end of the slot, where- guide slot, said drop wire being provided by the drop wire may be readily visible with a warp thread receiving opening at a 10 when the same becomes lowered, said means point below the indicating means.

5 being provided with a hook receiving opening to facilitate the raising of the drop wire, the opening being formed at a point

In testimony whereof I affix my signature.

OSTEEN J. PLAYER.
